UNITED STATES PATENT OFFICE.

WALTER KITTREDGE FOSTER, OF STONEHAM, MASSACHUSETTS.

CARRIAGE-WHEEL.

SPECIFICATION forming part of Letters Patent No. 309,705, dated December 23, 1884.

Application filed July 15, 1884. (No model.)

To all whom it may concern:

Be it known that I, WALTER KITTREDGE FOSTER, of Stoneham, in the county of Middlesex, of the Commonwealth of Massachusetts, have invented a new and useful Improvement 5 in Carriage-Wheels; and I do hereby declare the same to be described in the following specification and represented in the accompanying drawings, of which—

10 Figure 1 is a side view of a wheel provided with my invention, the nature of which is defined in the claim hereinafter presented. Fig. 2 is a side view; Fig. 3, a longitudinal section of a sector of the improved wheel. Fig. 4 is 15 a cross-section on line $x x$, Fig. 2.

In constructing carriage-wheels having steamed and bent fellys it has been customary to have the felly-joint midway between two next adjacent spokes, such spokes being 20 tenoned into the felly. In some cases the abutting ends of the felly at the joint have been inserted within a short tube of metal. In other cases a clip or piece of metal extended across the joint and bolted or riveted or otherwise connected or applied to the abutting 25 portions of the felly has been employed. By having the joint midway between the two next adjacent spokes, the felly parts next to it and between it and the said spokes are very liable 30 while the wheel may be in use to, both with the tire, be bent in toward the hub. The weak parts of the wheel-felly are not only the joint midway between the two spokes, but the mortised portions of the felly at the spokes.

35 In carrying out my invention I have no felly-joint midway between two next adjacent spokes; but I have between such spokes a voussoir, or arched piece of the felly, and two joints between it and portions of the felly projecting 40 toward each other from the spokes, such being as shown in the drawings, in which—

A is the felly, B the hub, C the spokes, and D the tire, of the wheel. The auxiliary or arched piece of felly is shown at E as directly between and abutting against two extremes, a , of the felly, beyond the two next adjacent spokes C, the two parts a being projected toward each other from the two spokes which are tenoned into the felly. 45

To hold the arched piece E in connection with the said parts a , I use at each end of the said piece a T-bolt, b , a washer, c , and a nut, d . The shank of the bolt goes through the joint and extends into the piece E and the part a at the joint, the bolt-head clasping the felly at the joint, all as represented. The parts a become short abutments for the arched piece E, their joints being in directions radial 50 to the axis of the wheel. The tire, when on 55 the felly, prevents the parts thereof at the joints from spreading apart.

In my improved wheel, there being no felly-joint midway between the two next adjacent spokes, there can then be little, if any, inward movement of the felly, to exert on it, at the parts of it joined to the spokes, a leverage tending to rupture or break such parts asunder. Therefore it will be seen that my improvement prevents the insetting of the 60 felly midway between the two spokes, and the 65 evil results usually following therefrom. 70

I claim as my invention—

A carriage-wheel having short portions of its felly extending toward each other from and between two next adjacent spokes, and also having between and jointed to and connected with such short portions a separate voussoir or arched portion of the felly, all being substantially as set forth. 75

WALTER KITTREDGE FOSTER.
